Primary Examiner — Darcey E Gottschalk*Assistant Examiner* — Vanessa Michelle Pursley(74) *Attorney, Agent, or Firm* — Parker D. McCrary(57) **CLAIM**

The ornamental design for a toothpaste carton, as shown and described.

DESCRIPTION

FIG. 1 is a perspective elevation view of a toothpaste carton with an opening;

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

Broken lines are used in the drawings to designate environmental structures or parts of a toothpaste carton that form no part of the claim.
